UNITED STATES PATENT OFFICE.

ANDREW TRACY, OF RICHLAND, IOWA:

TAKE-UP FOR SEWING-MACHINES.

SPECIFICATION forming part of Letters Patent No. 269,552, dated December 26, 1882.

Application filed October 3, 1882. (No model.)

To all whom it may concern:

Be it known that I, ANDREW TRACY, of Richland, in the county of Keokuk and State of Iowa, have invented certain new and useful 5 Improvements in Take-Ups for Sewing-Machines; and I do hereby declare that the following is a full, clear, and exact description of the invention, which will enable others skilled in the art to which it appertains to make and use 10 the same, reference being had to the accompanying drawings, which form part of this specification.

Figure 1 is a perspective view of my improved take-up for sewing machines, part of 15 the casing having been broken away so as to illustrate the working mechanism. Fig. 2 is a vertical sectional view, and Figs. 3, 4, and 5 are detail views.

Corresponding parts in the several figures 20 are denoted by like letters of reference.

This invention relates to take-ups for sewing-machines; and it consists in certain improvements in the construction of the same, which will be hereinafter fully described, and 25 particularly pointed out in the claims.

In the drawings hereto annexed, A represents the casing, having bearings for one end of the main operating-shaft B, carrying the disk C, carrying an eccentric roller, D, 30 engaging the heart-cam E of the needle-bar, which is thus operated.

The casing A is provided with bearings for a slide, F, moving vertically and having at 35 its upper end a laterally-adjustable plate, G, carrying a pin, H, upon which is mounted a friction-roller, I. Below the latter the slide F is provided with a pin, J. The said pin J and roller I engage an eccentric flange, K, adjustable upon the rear side of the disk C by means

of pins or bolts L, working in slots M in said 40 disk. In this manner the slide is operated, and its stroke may be regulated by properly adjusting the eccentric flange K and the roller I.

Rollers N may be arranged in the shell or casing adjoining the slide F, for the purpose 45 of reducing friction to a minimum. Slide F is provided with a notch, O, to accommodate the take-up lever P, which is pivoted in the casing, rear of said slide, and which projects through a slot in the front of the casing. The notch O 50 has a pin, Q, fitting in a slot, R, in the take-up lever, which is thus operated by the vertical reciprocating movement of the slide.

The end of the take-up lever has an eye, S, and notch T, covered by a flat spring, U, so as 55 to admit the thread easily and hold it securely. Tension and thread guides of suitable construction are to be provided.

The operation of my invention will be readily understood from the foregoing description 60 in connection with the drawings hereto annexed. It is simple in construction, convenient, and effective.

I claim and desire to secure by Letters Patent of the United States—

1. The combination, with the slide F, of the 65 disk C, having adjustable eccentric flange K, as set forth.

2. The disk C, having adjustable flange K, in combination with the slide F, having adjustable roller I and pin J, as set forth.

In testimony that I claim the foregoing as my own I have hereto affixed my signature in presence of two witnesses.

ANDREW TRACY.
